International Business Machines Corporation,
New York, N. Y., a corporation of New York

Application July 14, 1934, Serial No. 735,175

2 Claims. (Cl. 235—61.6)

This invention relates to improvements in tabulating machines and more particularly refers to adding and printing mechanisms for such machines.

- 5 One object of this invention is to provide novel means for accumulating duo-denominational amounts represented by perforated index points in two columns of a record card on a single accumulator element.
- 10 Another object is to provide novel means to read out a duo-denominational number standing on a single accumulator element and to control a plurality of printing means to print the different denominational orders of said amount.
- 15 Another object of the invention is to provide novel means to accumulate numbers of two denominational orders represented by perforated index points in two columns of a record card onto a single accumulator element and to control
- 20 two printing elements from said accumulator element to print each of the orders of the number standing on the accumulator element from a different printing element.

Other objects and advantages will appear from the following specification and drawings.

An embodiment of the invention is shown in the accompanying drawings in which:

Fig. 1 is a detail view of one of the printing elements and the mechanisms for operating said elements.

Fig. 2 is a facsimile of a fragment of a perforate record card for use in the machine.

Fig. 3 is a perspective view of the totalizer and totalizer read-out mechanism.

Fig. 4 is a detail view of the transfer or carry mechanism.

Fig. 5 is a detail view of a part of the carry mechanism.

Fig. 6 is a circuit diagram of the machine.

Fig. 7 is a diagrammatical representation of the timing of the cam operated contacts.

The herein disclosed invention is adapted to be used in connection with an electrically operated tabulating machine of the type disclosed in the patent to C. D. Lake and G. F. Daly, No. 1,976,617, issued October 9, 1934. The circuit connections (Fig. 6) peculiar to the instant invention are shown in heavy lines.

During analyzing operations the machine is controlled by a tabulating motor TM, which is controlled by a group of circuits including relays and cam operated contacts. During total taking operations the machine is driven by a reset motor also controlled by relays and cam con-

trolled contacts, illustrated in the upper portion of Fig. 6.

During analyzing or tabulating operations the usual perforated cards are fed successively past a set of upper analyzing brushes UB and then, 5 one card cycle later, past lower analyzing brushes LB. As the cards pass the lower brushes the items represented by the perforations may be entered into accumulators represented by accumulator magnets 10 and printed under the 10 control of printing magnets 11.

On total taking operations printing is controlled by the printing magnets in a manner to be more fully explained.

The twelfths are punched in two columns on 15 the card (Fig. 2), from 1 to 9 twelfths being punched in the right hand column 12, 10 and 11 twelfths being punched in both columns 12 and 13.

The totalizer wheel 14 (Fig. 3) has twelve positions from 0 to 11, inclusive the "0" position being left blank. Adding of twelfths from 1 to 9, inclusive, is effected in the normal manner. As the card passes the lower brushes LB the position of the index point determines the time 25 of closure of circuits. Representative plug connections for printing and adding are shown in Fig. 6 where connections 15 and 16 may be made between the lower brushes and plug sockets 17 and 18 respectively associated with the twelfths 30 columns 12 and 13 (Fig. 2) of the card.

Assuming that a hole is punched in the "6" position in the right hand column indicated at 12 (Fig. 2) which hole represents 6 twelfths, as the card passes the lower brushes LB a circuit 35 will be completed as the hole comes under the brush, extending as follows: from the right side of line 19, wire 20, lower card lever contacts 21, impulse emitter 22, lower brush contact bar 23, perforation in the card, connection 15, socket 40 17, wire 24, normally closed contacts 25, wire 26, printing magnet 11, to the left side of the line 27. The magnet 11 controls the type bar 28 (Fig. 1) to stop said bar in a position corresponding to the hole punched in that column. Printing from the left hand column 13 (Fig. 2) is effected in the same manner, however, a hole is punched in this column in the "1" position to represent the tenth order of 10 or 11 twelfths only.

The mechanism controlled by the printing magnet 11 is illustrated in Fig. 1. The type bars 28 are carried by a crosshead 29 which is mounted to slide vertically on rods 30. Spring-pressed arms 31 pivotally carried by the cross-

50

55

head 29 have their free ends supporting the lower ends of the type bars 28.

A listing shaft 32 and a total taking shaft 33 adapted to be operated by the TM motor and the reset motor respectively are provided to control the reciprocating movement of the crosshead 29 on listing and total taking operations respectively. A cam 34 fast on the listing shaft 32 and a cam 35 fast on the total taking shaft 33 are adapted to rock a shaft 36 by means of a follower mechanism 37. Arms 38 secured on the shaft 36 are connected by links 39 to the crosshead 29.

As the crosshead moves upwardly on tabulating operations the type elements 40 are carried successively past a printing position opposite a platen 41 in synchronism with the passage of the card past the lower brushes LB. Also ratchet teeth 42 pass the nose of a stop pawl 43.

20 Energization of the magnet 11 trips a latch 44 permitting the stop pawl 43 to engage one of the ratchet teeth 42 thus arresting the bar 28 with the proper one of the type elements 40, which in this case is the "6" element, opposite the platen 25 41 so that an impression may be made from said element by operation of the usual printing hammer 45.

At the time the circuit was completed through the perforation and through the printing magnet 30 11 a circuit was also completed from the plug 17 (Fig. 6), contacts 46 normally closed, through the accumulator magnet 10, to the left side of the line 27, thus energizing the accumulator magnet 10 which controls the following 35 described mechanism.

The time of closing the circuit to and energization of the print magnet 11 is independent of the closing of the circuit to the accumulator magnet 10.

40 A shaft 47 (Fig. 3) is driven in the usual manner in synchronism with the card feeding mechanism so as to make one revolution for each card passing through the machine. A clutch element 48 is mounted on the shaft 47 in such a 45 manner as to rotate therewith but slidable longitudinally of said shaft to engage a clutch element 49 integral with a gear 50. The gear 50 meshes with a gear 51 secured to the indexed totalizer wheel 14 freely mounted on a shaft 53. The 50 clutch 48 is normally urged toward the clutch 49 by a pivoted lever 54 under the influence of a spring 55 but is prevented from so moving due to an armature latch 56 which normally engages a block 57 to hold the lever 54 in the position 55 in which it appears in Fig. 3. When the magnet 10 is energized the latch 56 frees the lever 54 to the spring 55 which rocks the lever counter-clockwise engaging the clutch 48 with the clutch 49.

60 The accumulator mechanism for the 12ths accumulator differs from the usual Hollerith structure in that the accumulator wheel 14 and the read-out commutator 104 are each provided with 65 twelve positions instead of the usual ten positions. The machine operates on a 14-point cycle during which the shaft 47 makes one complete rotation. The ratio of gears 50 and 51 have been changed from the usual Hollerith structure so that rotation 70 of the gear 50 through one point of a cycle advances the accumulator wheel 14 one position or one twelfth of its rotation instead of one tenth. Also the ratio of the gears 50 and 97 in the present 75 twelfth accumulator is such that one point of the cycle advances the gear 97 and the commutator

brushes one twenty-fourth of their rotation or one position.

At the "0" point of each rotation of the shaft 47 the clutch 48 is mechanically disengaged in the usual manner so that the amount of rotation imparted to the index wheel 14 is dependent upon the time during the cycle at which the magnet 10 is energized. Thus, if the magnet 10 is energized at the "6" index position on the card, the wheel 14 will be advanced six steps. 10

Adding ten twelfths

It was disclosed above how adding digits from 1 to 9 punched in the right hand or units column 12 is effected in the usual manner well known in 15 the type of machine to which the present invention is adapted to be applied. The manner of adding ten twelfths into the totalizer wheel 14 will now be explained.

In order to represent ten twelfths in columns 20 12 and 13 on the card (Fig. 2) a hole is punched in the "1" position in the left hand column designated 13. When this hole passes under the upper brushes UB (Fig. 6) a circuit is completed from the right side of the line 19, upper card lever contacts 60, contacts 61, closed at the "1" position in the cycle, wire 62, coil of magnet 63, wire 64, through the hole in the card, upper brush contact bar 65, contacts 66, wire 67 to left side of line 27. This circuit closes contacts 68 setting up 30 a holding circuit through holding coil 69 extending as follows: line 19, contacts 70, wire 71, contacts 68, coil 69, wire 72, to line 27. One point before the "9" index point position of the card reaches the lower brushes LB cam contacts 73 35 close completing a circuit as follows: line 19, contacts 70, wire 71, contacts 68, wire 74, contacts 73, accumulator magnet 10 to line 27. This energizes the magnet 10 one point earlier in the card cycle permitting the clutch 48 to engage clutch 49 40 and rotate the totalizer wheel 14 ten spaces or ten twelfths of one rotation since clutch 48 is spring held in engagement with clutch 49 until mechanically restored at the "0" point of the cycle. 45

The contacts 70 are opened during the cycle, opening the circuit through the holding magnet 69.

Adding eleven twelfths

Eleven twelfths is represented by punching a 50 hole in the "1" positions of both columns 12 and 13. When a card punched in this manner passes the upper brushes UB the hole in the "1" position in column 13 sets up the same circuits described above for adding ten twelfths onto the wheel 14. 55 In addition the hole in the "1" position in the right hand column 12 sets up the following circuit: line 19, contacts 60, contacts 61, wire 62, wire 75, magnet 76, wire 77, upper brush contact bar 65, contacts 66, wire 67 to line 27. 60

Energization of magnet 76 closes its contacts 78 setting up a holding circuit through a holding magnet 79 extending as follows: line 19, contacts 70, wire 71, contacts 68, contacts 78, magnet 79, wire 80, to line 27. This circuit is maintained 65 until contacts 70 open on the following cycle which occurs after the contacts 73 are closed and shortly before the "1" index point position of the following card passes the upper brushes. Early in the next cycle, on which cycle the card 70 passes the lower brushes, a pair of cam operated contacts 81 close setting up a circuit from line 19, contacts 70, wire 71, contacts 68, contacts 78, wire 82, contacts 81, carry magnet 83 to line 27.

Referring now to Fig. 4 energization of magnet 75

83 rocks a latch arm 84 to release an arm 85 pivoted on the shaft 53 to a spring 86 which spring immediately rocks the arm 85 clockwise against a ball 87 extending between a pair of arms 88 pivoted on the shaft 53. The arm 85 carries a spring-pressed pawl 90 cooperating with a ratchet 91 secured to the totalizer wheel 14. One of the arms 88 is connected by a link 92 (Fig. 5) to a bell crank 93 which carries a roller 94 cooperating with a cam 95 fast on a shaft 96.

The ball 87 normally is in the position in which it appears in Fig. 4 but just after the "0" index point position on the card passes the lower brushes the cam 95 rocks the bell crank 93 clockwise rocking the ball 87 counterclockwise. At this movement the ball 87 picks up the arm 85 and carries it counterclockwise therewith, the pawl 90, which was moved clockwise to position to the left of the next tooth on the ratchet 91 when the arm 85 was released, now advances the wheel 14 one step completing the addition of eleven to said wheel.

Total printing

A gear 97 (Fig. 3) rotatably mounted on a shaft 98 meshes with the gear 50. Secured to the sides of gear 97 are two disks 99 of insulating material each of which disks carries a brush holder 100 having two brushes mounted therein. These brushes are adapted to contact segments 101 in a moulding 102 and segments 103 in a moulding 104, both of which mouldings are suitably supported in the machine. The brushes are also adapted to contact conductors 105 and 106 to complete circuits to be fully described later. The 25 pairs of segments 101 and 103 correspond in number to the number of index positions on the wheel 14; that is, twelve positions numbering from "0" to "11", inclusive, the "0" position on the wheel being left blank. Obviously the gear 97 and the 30 brush structure mounted thereon will receive an angular displacement corresponding to the displacement of the totalizer wheel 14 on tabulating operations. The segments 101 and 103, and the conductors 105 and 106 are shown in developed form in the circuit diagram (Fig. 6). It 35 will be noted that several denominational order read-out commutators are illustrated in this development. The digital segments corresponding to the same digits are connected together by 40 common conductors 107. Thus, all the "9" segments are in multiple, all the "8" segments are in multiple, etc.

An impulse emitter 108 shown diagrammatically in Fig. 6 is driven synchronously with the movement of the type bars 28 past printing position during total taking operations. The emitter 108 consists of a double brush structure 109 which may be mounted on the total taking shaft 33 (Fig. 1). One of the brushes 109 when rotated, successively contacts segments 110 as the corresponding type elements pass through printing position during total taking operations.

Each segment 110 is connected to the correspondingly numbered conductor 107 so that each 65 of the commutator segments 101 receives a timed impulse from the emitter at the time when the type corresponding to the setting of the totalizer wheel is passing the printing line.

In order to print fractions of twelve from the 70 setting of the single totalizer wheel 14 on two type bars 28 the segments 101 and 103 associated with the twelfths totalizer wheel 14 are connected in a different manner. Referring to Fig. 6 it may be seen that the "10" segment 103 is connected to the "11" segment 103 and this segment

is connected to the "11" segment 101 which is connected by a wire 111 to the "1" segment 101. This segment is connected to the common conductor 107 for the digit "1". The segments 103 from "0" to "9", inclusive, are not connected to their respective conductors 107, nor is the "0" segment 101 connected to its conductor 107. The "1" to "9" segments 101, however, are connected to their respective conductors 107.

Three examples of total printing from the 10 commutators 102-104 will be given. These are: first, when the totalizing wheel 14 stands at a digit from "1" to "9" inclusive; second when the totalizer stands at 10 and third, when the totalizer stands at 11.

During total taking operations, a relay 112 is energized to connect the common conducting strips 105 and 106 to their corresponding printing magnets 11 and 11a, by closing contacts 113. A representative circuit will now be traced to 20 illustrate the manner in which the printing mechanism may be actuated from the total taking devices when the totalizer stands at one of the digits from "1" to "9".

Assuming that the totalizer is standing at "6" 25 during a total taking cycle, as the brushes 109 of the emitter 108 rotate in synchronism with the operation of the printing mechanism, a circuit will be completed from line 19, contacts 114, switch 115 now closed manually for total taking cycles, common segment 116, brushes 109, the "6" segment 110, the "6" conductor 107, "6" segment 101, brushes carried by the right hand holder 100 (Fig. 3), segment 105, contacts 113, wire 26, printing magnet 11 to the line 27. In this manner the digital value "1" to "9" standing on the accumulator wheel 14 will be printed by energization of magnet 11 as set forth above for listing cycles. Since the 103 segments "1" to "9" are 30 not connected to the bars 107 the left hand type bar (not shown but which is exactly like the bar shown in Fig. 1) will automatically go to its "0" position which in this case is left blank, since, in printing fractional parts of twelve, only the digit "1" will be printed in the tens position.

Assuming now that the totalizer wheel 14 is standing at "10", it will be noted that the "10" and "11" segments 101 and 103 are not connected to a corresponding conductor 107. As the brushes 109 contact the "1" segment 110 a circuit is 35 made from line 19, contacts 114, switch 115, the "1" segment 110, the "1" conductor 107, the "1" segment 101, wire 111, "11" segment 101, "11" segment 103, "10" segment 103, bar 106, contacts 113, wire 117, printer magnet 11a to line 27. 40 This energizes the magnet 11a as the "1" type element associated with the "tens" order is passing the printing line thus printing "1" in the left hand column.

The "0" segment 110 is not connected to its 45 conductor 107, consequently, no impulse will be emitted when the brushes 109 pass this segment. However, the units type bar controlled by magnet 11 will be automatically stopped in "0" position thus printing "10" indicating the ten twelfths 50 standing on the totalizer wheel.

When the totalizer wheel 14 is standing at "11" and the machine is operated to print the total, the following circuits will be made to effect the printing of "11", when the brushes 109 contact 55 the "1" segment 110: line 19, contacts 114, switch 115, the "1" emitter segment 110, "1" bar 107, "1" segment 101, wire 111, the "11" segments 101 and 103. Here the circuit splits to bars 105 and 106, contacts 113, wires 26 and 117, printer mag- 60

nets 11 and 11a to line 27, thus energizing both printer magnets when their type bars 28 are in the "1" position to effect the printing of "11" representing eleven twelfths.

5. While there has been shown and described and pointed out the fundamental novel features of the invention as applied to a single modification, it will be understood that various omissions and substitutions and changes in the form and details 10 of the device illustrated and in its operation may be made by those skilled in the art without departing from the spirit of the invention. It is the intention therefore to be limited only as indicated by the scope of the following claims.
15. What is claimed is as follows:
1. In a machine controlled by records having duo-decimal perforations arranged in two columns, a single accumulator wheel to receive duo-decimal numbers, means to sense each of said 20 columns of the records, means controlled by the sensing means for one column upon detecting a perforation to advance the accumulator wheel ten steps, and means controlled conjointly by the sensing means for both columns upon detecting 25 perforations in both columns to advance the accumulator wheel an additional step.

2. In a cyclically controlled machine controlled by records having duo-decimal value representing perforations arranged in units and tens columns, an accumulator wheel to receive duo-decimal values, means to operate the accumulator 5 wheel to advance said wheel, means to sense the duo-decimal perforations in one cycle of machine operation, other means to sense the duo-decimal perforations in the next cycle of machine operation, means controlled by the sensing means for 10 the tens column of said first named sensing means upon detecting a perforation to control the operating means to advance the accumulator wheel ten steps, means controlled conjointly by the sensing means in both columns of said first 15 named sensing means upon detecting perforations in both columns to advance the accumulator wheel an additional step, and means controlled by the units column sensing means of said other sensing means upon sensing a record having a perforation in the units column only to control the operating means to advance said accumulator wheel an extent in accordance with the perforation sensed.

25 VICTOR O. WILKERSON.
